UNITED STATES PATENT OFFICE.

JOHN CORNELIUS WILSON, OF BOSTON, MASSACHUSETTS, ASSIGNOR TO
THE MUNICIPAL SIGNAL COMPANY, OF PORTSMOUTH, N H.

MUNICIPAL-TELEGRAPH APPARATUS.

SPECIFICATION forming part of Letters Patent No. 331,356, dated December 1, 1885.

Application filed April 28, 1884. Serial No. 129,500. (No model.)

To all whom it may concern:

Be it known that I, JOHN C. WILSON, of Boston, county of Suffolk, State of Massachusetts, have invented an Improvement in Municipal-Telegraph Apparatus, of which the following description, in connection with the accompanying drawings, is a specification, like letters on the drawings representing like parts.

10 My invention relates to a telegraph apparatus especially intended for use in cities in connection with the police-service, the invention being shown embodied in a signal-box intended to be connected in an electric circuit 15 with the police station-houses. The signal-box is intended to be accessible to all citizens, for the purpose of enabling them to summon police aid at the sub-station or locality where the box is situated, each box being adapted to 20 transmit a distinct signal, preferably representing a number that identifies the box and its locality, like the well-known signal-boxes used in fire-alarm-telegraph systems. In addition to the signal that is accessible to all persons, there 25 is also a series of special signals, accessible only to authorized persons who have keys giving access to the part of the box containing the devices for transmitting such signals.

The invention consists partly in a box containing signal-transmitting mechanism having two independent operating devices, one for sending a signal, herein called the "main" or "box" signal, and the other for sending the said main signal, in connection with any desired one of a series of special signals, combined with a local audible signal or alarm, and mechanism whereby it is set in operation when the box or main signal is sent. As herein shown, the box has a door, which, for the sake of 35 distinction, may be called the "citizen's door," affording access to the device for transmitting the box-signal, the said door being provided with a latch, and means to produce a local alarm, when the said latch is operated to permit the door to be opened, on the signal-seat. By this means a loud alarm is sounded whenever the box is operated by a citizen, thereby attracting the attention of all persons in the neighborhood, and thus deterring persons

from giving an unnecessary alarm, and also 50 serving in itself as a very efficient call for aid.

The invention also consists in the combination, with the box containing the citizen's door and multiple-signaling devices before mentioned, of a door, called, for the sake of 55 distinction, the "policeman's door," provided with a suitable lock for affording access to the said multiple-signaling devices.

Figure 1 is a front elevation of a signal-box embodying this invention, the policeman's 60 door at the front of the box being opened and a portion of the dial that indicates the special signals being broken away to show the interior mechanism of the box; Fig. 2, a partial section of the box, showing the internal mechanism 65 in end elevation; Fig. 3, an end elevation of the box, showing the citizen's door open; Fig. 4, a plan view of the multiple-signaling mechanism; Fig. 5, a view of the same parts, as seen looking upward from beneath; Fig. 6, 70 details of a portion of the signaling-surfaces, and Fig. 7 a diagram illustrating the circuits.

The box A, of suitable size to contain the working parts, is provided with two doors, B C, affording access to different parts of the 75 interior mechanism, the former, called for distinction the "policeman's door," affording access to the entire interior of the box, and being provided with a lock, D, that can only be unlocked by a special key, with which policemen or other authorized persons will be provided. The door C, herein called the "citizen's door," will be provided with a latch, e, operated by a handle, E, accessible at the outside of the box; the said handle in turning 80 being adapted to operate an alarm at the box. The mechanism of the said door may be of any well-known kind—such, for instance, as shown in Letters Patent No. 164,406, dated June 15, 1875, it not being herein specifically 85 shown and described, as the particular mechanism to operate the latch and local alarm forms no part of my invention.

The signal-transmitting mechanism in the box consists, essentially, of a train of wheel-work, a a', of usual construction, one of the arbors of which carries a series of wheels or disks, b b', the peripheries of which are notched

or cut out, as best shown in Fig. 6, they operating to produce a series of breaks or interruptions in an electric current passing over a circuit, of which the said wheels and springs 5 form a part. The said wheel b , which, as will be shown later on, is always in circuit, has its periphery provided with short notches arranged to produce a number-signal identifying the box, and herein called the "main" or 10 "box" signal, it being such as employed in fire-alarm telegraphs, while the wheels b' have their peripheries notched to produce special signals, which may consist of long and short changes—such as used in the Morse alphabet— 15 they preferably producing signals that contain dashes, so that they may be readily distinguished from the number-signals, which consist wholly of dots. The actuating weight or spring for the said train is wound by means 20 of a crank or finger-piece, d , accessible through the side of the box when the citizen's door C is open, as shown in Fig. 3, so that a citizen having opened the said door may wind the 25 said actuating weight or spring and set the clock-work in motion to transmit the number-signal of the box from the break-wheel b , the other wheels, b' , then being out of circuit, as will be hereinafter explained. The said train of wheel-work may also be wound or operated 30 by a finger-piece, e , connected with the same shaft as the crank d , as shown in Figs. 1 and 2, the said finger-piece e being accessible only when the policeman's door B at the front of the box is open.

35 The springs c' , co-operating with the wheels b' , are each connected, as best shown in Fig. 7, with one of a series of springs, f , resting on the surface of a circuit-selecting device, g , (shown as a drum,) the arbor or shaft g' of 40 which is provided with a pointer, g^2 , (see Figs. 1 and 2,) by which the said drum may be rotated, the said pointer moving over the face of the dial F , Fig. 1, upon which are marked or indicated the special signals that are to be 45 transmitted by the wheels b' . The said shaft g' is provided with a toothed stop-wheel, g^3 , which is caused, by a co-operating yielding stop, g^4 , to hold the drum and pointer in any position to which it may be turned, the said 50 pointer being then opposite one of the signals on the dial. The drum g is provided with a conducting-ring, h , normally in contact, when the door B is open, with a spring, i , connected with the main line or circuit entering or leaving 55 the box, and the said ring h is connected with a series of contact-pieces, h' , arranged around the periphery of the drum, as shown in Fig. 7, where the surface of the drum is represented as developed or laid out flat.

60 Each of the said contact-pieces h' is in the path traversed by a corresponding one of the springs f , connected with the springs c' , and each one of the said contact-pieces is brought into contact with one of the springs f when 65 the drum is turned by the pointer g^2 to one particular position corresponding to one of the signals on the dial.

The circuit and operation of the break-wheels is shown in the diagram, Fig. 7. The main line L , entering the box at one side, is electrically connected with the entire series of wheels $b b'$, and the spring c , co-operating with the wheel b , is connected by wire 2 with the line L' , leaving the box at the other side. The spring i , co-operating with the ring h , is connected by 70 wire 3 with the line L' , while the springs c' are connected by wires 4 with the springs f , resting on the drum g . When, by moving the drum g , any desired one of the contact-points h' is brought into connection with the corresponding spring, c' , the circuit will be completed through the wheel b , spring c , and wire 2 to the line L' , and also through that one of the wheels b' which was selected by the movement of the drum g , and through the corresponding spring, c' , wire 4, spring f , contact-point h' , ring h , spring i , and wire 3 to the line L' . 80

The break-wheel b has a portion of its periphery removed, as shown in Fig. 6, thus 90 leaving the circuit open between it and the spring c during a considerable portion of its revolution, and the projections or raised portions of the wheels b' are arranged to co-operate with their springs c' during this portion 95 of the rotation of the wheels $b b'$.

In order to prevent the wheels b' from operating when the door B is closed and the crank or winding-piece d operated by the citizens, the pointer and drum may be mechanically 100 turned to a particular point upon the closing of the door by a cam, k , and projection m , as shown in Letters Patent No. 288,536, November 13, 1883, thus causing the same signal to be always given when the door B is closed. 105 As shown, in this instance the wheels b' are also wholly removed from the circuit when the door B is closed, the said door being provided with a circuit-controlling device, consisting in this instance of a projection, p , which will raise 110 the spring i from contact with the ring h , thus leaving the wheel b alone in circuit when the door B is closed. Thus when the policeman's door B of the box is closed the citizen can send only the main or box number signal, which is 115 understood as a call for police aid of some nature, and when the door B is first opened the pointer will stand at a definite point, preferably corresponding to the patrol-signal, so that the policeman may transmit a signal 120 merely for indicating his presence at the box without disturbing the pointer, which only need be moved when some special signal is to be sent.

It will be understood that the number-signal 125 is always sent in connection with the special signals. When, as is usually the case, the signals are received on a register that prints when the circuit is open, the citizen's signal will consist of a long dash, together with the 130 series of dots representing the box-numbers. The box A also contains a transmitting-telephone, T , of any usual construction, the said telephone being preferably placed with its

mouth-piece at the rear of an elastic or flexible sound-deadening diaphragm, M, preferably composed of a thick piece of combined rubber and fabric, against which the person talking may press his face, the said diaphragm surrounding his mouth and concealing its movements, and also effectually cutting off the sound from the outside of the box, so that he can talk without being heard or understood by people in the neighborhood.

The diaphragm has an opening at its middle of about the same size as the mouth-piece of the telephone, so that it does not interfere with the access of sound to the said telephone. 15 A receiving-telephone, T', is also provided, and the said telephone may be connected in the same circuit as the transmitting mechanism of the box, or may be in an independent circuit used only for telephone communication.

The transmitting-telephone may be either a magneto-telephone or the usual microphone or battery transmitter, in which case the battery-cell t will also be inclosed in the box A, 25 which will preferably be lined with felt or other non-conducting material. This non-conducting lining H will serve both as a non-conductor of heat, preventing the battery from freezing, and also as a non-conductor of sound, 30 affording a further protection against the danger of bystanders overhearing the conversation carried on through the telephone.

I claim—

1. A signal-box containing a signaling device for transmitting a box-signal characterizing the box or station, and a multiple-signal apparatus for transmitting any desired one of a number of special signals, combined with a citizen's door provided with a latch and local 35 alarm mechanism operated from the outside of the box, the said door affording access to the box-signal only, substantially as described.

2. A signal-box containing a clock-work or motor having two independent starting devices accessible from different parts of the box, 45 combined with independent doors, one affording access to each of the said starting devices, one of the said doors requiring the co-operation of a key or equivalent to effect its opening, and the other door being provided with a latch and alarm mechanism and knob or handle for operating the same, substantially as described.

3. In a signal-transmitter, a clock-work or motor and series of break-wheels rotated thereby, combined with a series of co-operating contact-springs and a circuit-selecting device, the said wheels being all connected with the main-line circuit at one side of the box and one of the said springs and the circuit-selecting device being connected with the main line at the other side of the box, one of the said break-wheels being always in circuit, and any desired one of the others being placed in circuit by the selecting device, substantially as described. 55

4. A clock-work or motor and series of break-wheels or contact-surfaces adapted to be moved simultaneously by the said motor and a series of co-operating contact-springs, combined with a circuit-selecting device for a portion of the 60 said springs and wheels, and a circuit-controlling device which when operated removes the springs and wheels affected by the said circuit-selecting device from the circuit, substantially as described. 70

5. A signal-transmitting apparatus comprising a series of signaling devices, each consisting of a notched or irregular surface and co-operating contact-piece, and a motor for moving the one relatively to the other, one of the said contact-surfaces and springs being always in circuit for producing an unchangeable main signal, combined with a selecting device, by which any desired one of the remaining devices may be placed in condition for producing a variable or special signal, and a circuit-controlling device for the latter, or special signaling devices by which the entire series may be removed from circuit, placing the apparatus in condition to transmit the main or unchangeable signal only, substantially as described. 75 80 85

6. A series of simultaneously-moving break-wheels and co-operating contact-springs, combined with a circuit-selecting drum, a pointer connected therewith, and a dial co-operating 95 with the said pointer having a series of signals corresponding with those produced by the different break-wheels, substantially as described.

In testimony whereof I have signed my name 100 to this specification in the presence of two subscribing witnesses.

JOHN CORNELIUS WILSON.
